UNITED STATES PATENT OFFICE

FRED V. SCHUBERT, OF BOSTON, MASSACHUSETTS

FORM FOR CONCRETE COLUMNS

Application filed November 24, 1928. Serial No. 321,565.

This invention relates to forms for use in making concrete columns.

The forms ordinarily used for this purpose are made of wood. Their erection and subsequent removal after the column has set not only is expensive in materials but also in time and labor. With a view to reducing this expense a great variety of metal forms have been proposed but so far as I have been able to learn they have met with only indifferent commercial success.

In attempting to use forms of this construction it has been found that many of them buckle and the seams open under the very heavy hydrostatic pressure to which they are subjected prior to the setting of the concrete. Many of them also are too complicated or too expensive to manufacture to be practical. In most of these prior constructions, also, the sections are secured together by threaded bolts and nuts which rust and are the cause of much trouble.

The present invention deals with this problem and it aims to devise a thoroughly practical solution for it. It provides a form which can be erected or disassembled with a minimum of labor, which has ample strength and rigidity to withstand the hydrostatic pressure of the concrete mixture while it is still in a semi-fluid mass, and which, in addition to being adjustable for columns of different dimensions and shapes, still is economical to manufacture.

The nature of the invention will be readily understood from the following description when read in connection with the accompanying drawings and the novel features will be particularly pointed out in the appended claims.

In the drawings,

Fig. 1 is a side view of a form for a column of square cross section, this form being constructed in accordance with the present invention;

Fig. 2 is a plan view of the form shown in Fig. 1;

Fig. 3 is a plan view of bars used in the girdle shown in Figs. 1 and 2;

Fig. 4 is a view similar to Fig. 1 show-

ing the provision for adjusting the form vertically;

Figs. 5, 6 and 7 are angular views of units used in the form shown in Figs. 1, 2 and 4;

Fig. 8 is a plan view of a key which preferably is used in securing the sections of the form together;

Figs. 9 and 10 are plan views of wedges used in the construction illustrated;

Fig. 11 is a perspective view of a modified form of girdle; and

Fig. 12 is a perspective view of the yoke shown in Fig. 11.

The drawings show the invention as embodied in a form designed for the making of square concrete columns, although it will be understood that it is equally useful in making columns of other cross sectional shapes. Referring first to Figs. 1 and 2, it will be seen that the form there shown comprises a series of sheet metal sections or units 2 each of channel section. These units are relatively long and narrow and extend longitudinally of the column. The number of these units used will necessarily depend upon the shape and dimensions of the column and the dimensions of the units themselves. In the form illustrated in Fig. 2 three of these units are used at each side of the column. At the corners of the column additional sheet metal units 3 of angular section are used.

It will be observed that these units are arranged edge to edge with their marginal flanges extending backwardly away from the column and the flanges of adjacent units abutting against each other. In order to secure the units together the flanges are perforated or slotted to receive fastening devices, this slotted construction being clearly shown in Figs. 5, 6 and 7. The slots are similarly located in all of the units so that the slots of abutting flanges of adjoining units will register with each other. Preferably keys 4 and wedges 5 (see Figs. 8 and 9) are used to fasten these units together. These parts preferably are made out of relatively heavy sheet metal. Each key, as shown in Fig. 8, has a head 6 and a shank 7 of suitable dimensions to fit in the slots in the

flanges of the units, this shank being slotted, as shown at 8, to receive the key 5, and the end portion of the shank being tapered. The keys are inserted in the registering slots of abutting flanges of the units and the wedges 5 are then driven into the slots in the keys, thus clamping each pair of abutting flanges between the head of the key and the wedge.

All of the units are secured together in this manner, and it will be clear from an inspection of the drawings that this arrangement permits the very rapid and secure fastening of the units together. The slots in the flanges are so spaced that the keys may be inserted at suitable intervals.

In order to support the form against buckling and the disrupting action of the hydrostatic pressure to which the form necessarily is subjected in practice and which is very severe in the case of long columns of large cross section, a series of girdles or belts is provided. In the construction shown in Figs. 1 and 2, each belt consists of four bars indicated, respectively, at 10, 11, 12 and 13. The bars 10 and 12 are substantially alike, and the bars 11 and 12 also are duplicates of each other but are of different construction from the bars 10 and 12. That is, the latter bars are slotted, as best shown at 14, Fig. 1, to receive the end portions of the bars 11 and 13. These bars are arranged horizontally so that they bear edgewise against the form and their overlapping portions are provided with diagonal slots 15, preferably arranged at an angle of approximately 45° with reference to the edges of the bars. The slots of the overlapping portions of the bars at the corners of the form can readily be brought into register with each other, and the bars are secured in this relationship by large wedges 16, one wedge being driven down through each pair of registering slots. As best shown in Fig. 2 the slots in which the wedges 16 are located are directed, respectively, toward the corners of the form. It will be clear, therefore, that as these wedges are driven down each wedge will tend to slide the bars which it engages along the sides of the form toward its respective corner. This tightens the girdle firmly around the form and holds the girdle in its tightened condition.

A series of these girdles are used on each form, the girdles being spaced vertically from each other. If desired certain of the girdles can be made to rest on the keys 4 as shown, for example, in the lower part of Fig. 1. Obviously the number and spacing of the girdles used will depend upon the dimensions of the column being poured, a long column of large cross section requiring a closer spacing of the girdles, particularly at the lower part of the form, than a shorter or smaller column.

The erecting of a form of this construction

will be obvious from the foregoing description. This erecting operation can be performed very rapidly, and after the column has been poured and set the form can be taken down quickly by knocking out the wedges 16 and removing the girdles, and then knocking out the wedges 5 at the corners of the form so as to release the side sections of the form from each other.

The units 2 and 3 may conveniently be made of twenty gage sheet steel, although other materials and different thicknesses can also be used. The bars for the girdles should be made of heavier stock. While the units 2 can be made of any suitable width, it will be found convenient for ordinary construction purposes to use units of three and four inches in width. With these two sizes forms can be built for the pouring of a great variety of sizes and shapes of columns. It should be observed that since the units do not overlap each other at the face of the column but are arranged in an edge to edge or abutting relationship, the form produces a smooth faced column without the longitudinal grooves which are made in the faces of the columns when overlapping plates or sections are used. At the same time this construction effectually resists the tendency of the concrete to buckle or spread the form, due partly to the flanged construction of the units and partly, also, to the fact that the edges of these flanges bear against the edges of the girdle bars 10, 11, 12 and 13, this arrangement being particularly effective in resisting the hydrostatic pressure created within the form when the concrete is poured. The use of wedges to hold the units together and to fasten and tighten the girdle sections is a great convenience both in erecting and taking down the forms.

Usually the units 2 and 3 are shorter than the height of the column to be poured, and in order to make the form adjustable for height, it may be made in upper and lower sections, the units of the upper section being telescoped with those of the lower section. This arrangement is shown in Fig. 4, from an inspection of which it will be seen that the units 2 of the upper section of the form are sprung inside the corresponding units 2' of the lower section. This can readily be done due to the nature and construction of the units. Thus in the region A, Fig. 4, where the upper and lower sections overlap each other, each key 4 and its cooperating wedge 5 will clamp four flanges together, as clearly shown in the drawings. At the upper ends of the flanges of the lower units 2' there will be narrow tapering cracks 17, Fig. 4, between the flanges of the upper units 2. If these units, however, are made of twenty gage sheet steel, as above stated, the maximum width of these cracks is so small that they cause no trouble in actual practice.

It will now be evident that the invention provides a metal form for making concrete columns which is economical to manufacture, convenient to handle, which can be used in the pouring of a great variety of sizes and shapes of columns, and which results in the saving of time, labor and materials as compared with the use of wooden forms. This has definitely been established in the practical use of the invention.

While I have herein shown and described a typical embodiment of my invention, it will be understood that this embodiment has been disclosed rather by way of illustration than limitation and that the invention may be embodied in a great variety of other forms without departing from the spirit or scope thereof. For example, the changes required to produce other flat sided columns will be obvious. Round columns can also be made by using units of different shape, each unit having an inner surface which is a section of a cylinder with its flanges projecting on radii of the cylinder.

Fig. 11 shows a somewhat different form of girdle which has the advantage of being lighter in weight than the girdle construction above described and still operating in essentially the same manner. In this arrangement each pair of girdle bars 19 and 20 are connected together at one corner of the form by a pivot pin, bolt or rivet 21 so that these two members can swing. The two pivots 21 are arranged at diametrically opposite corners. At the other corners the bars 19 and 20 overlap and these overlapping portions are provided with slots 15 like those formed in the girdle bars previously described. Preferably a yoke 22, Fig. 12, is used at each of these corners to embrace the bars, the yoke being open at one side to permit the bar 20 to pass through it and having a slot 23 at its opposite side to permit the end of the bar 19 to pass through. A diagonal slot is provided in this yoke to receive the corner wedge 16 which is guided in the yoke and is driven through the registering slots 15 of the two bars 19 and 20 so as to tighten the girdle about the form in the same manner as in the construction above described.

These and other modifications may be made within the spirit and scope of the invention.

Having thus described my invention, what I desire to claim as new is:

1. A form for making flat sided concrete columns, comprising a plurality of sheet metal units of channel section extending longitudinally of each side of the form to support the sides of the column, additional sheet metal units of angular section extending longitudinally of the form at the corners of the column, said channel units being arranged edge to edge with their flanges in

abutting relationship, and said angular units being arranged with one flange abutting the flange of a channel unit in each of two sides of the form, said flanges being slotted to receive keys, and wedges cooperating with said keys to secure the flanges of adjacent units through the sides and at the corners rigidly but releasably together, thereby to provide a normally self-sustaining form.

2. A form for making flat sided concrete columns, comprising a plurality of sheet metal units of channel section extending longitudinally of each side of the form to support the sides of the column, additional sheet metal units of angular section extending longitudinally of the form at the corners of the column, said channel units being arranged edge to edge with their flanges in abutting relationship, and said angular units being arranged with one flange abutting the flange of a channel unit in each of two sides of the form, means for removably fastening the flanges of said units throughout its sides and at the corners, rigidly together, thereby to provide a normally self-sustaining form, and girdles encircling said form and spaced longitudinally thereof, each of said girdles comprising bars bearing against the outer edges of said flanges, and means for tightening said girdles about said form.

3. A form for making concrete columns, comprising a plurality of sheet metal units extending longitudinally of each side of the form for supporting the sides of the column, means connecting the units of each side together, and means connecting each complete side to an adjacent side of the form, thereby to provide a normally self-sustaining form, a girdle encircling said form and comprising bars bearing edgewise against the sides of the form, said bars having inclined slots formed therethrough, the slots in overlapping portions of the bars being adapted to be brought into register, wedges located in the registering slots and cooperating with the bars to crowd them against the sides of the form and thereby to tighten the girdle around the form, and a yoke embracing the overlapping portions of a pair of said bars, said yoke being slotted to receive and guide the wedge which acts on said overlapping portions of said bars.

4. A form for making flat sided concrete columns, comprising a plurality of sheet metal units extending longitudinally of each side of the form for supporting the sides of the column, means connecting the units of each side together, and means connecting each complete side to an adjacent side of the form, thereby to provide a normally self-sustaining form, and a girdle encircling said form and comprising bars bearing edgewise against the sides of the form, said bars being overlapped upon each other at corners of the form and having diagonal slots formed

- through them and arranged to be brought into register with each other, the registering slots at said corners of the column being directed, respectively, toward the corners of the column, wedges in said registering slots for tightening the girdle around the form, and a yoke embracing the overlapping portions of a pair of said bars and slotted to receive and guide the wedge which acts on said overlapping portions of said bars. 5
5. A form for making flat sided concrete columns, comprising a plurality of sheet metal units extending longitudinally of each side of the form for supporting the sides of the column, means connecting the units of each side together, and means connecting each complete side to an adjacent side of the form, thereby to provide a normally self-sustaining form, a girdle encircling said form and comprising bars bearing edgewise against the sides of the form and having portions overlapping one on the other, slots formed diagonally in said bars in such positions that the slots in overlapping portions of the bars may be brought into register with each other at a corner of the form, wedges located in said registering slots and cooperating with the overlapping portions of the bars to tighten the girdle on the form, yokes 10
- cooperating with the overlapping portions of each pair of bars at certain corners of the form, each yoke being open at one side to receive one bar and slotted at its opposite side to permit the end of the other bar to pass through it, and having a second slot to register with said diagonal slots in said overlapping portions of the bars to receive and guide a wedge extending through the slots in said yoke and said overlapping portions of the bars. 15
6. A form for making flat sided concrete columns, comprising a plurality of sheet metal units of channel section extending longitudinally of each side of the form to support the sides of the column, additional sheet metal units of angular section extending longitudinally of the form at the corners of the column, said channel units being arranged edge to edge with their flanges in abutting relationship, and said angular units being arranged with one flange abutting the flange of a channel unit in each of two sides of the form, means for removably fastening the flanges of said units throughout its sides and at the corners, rigidly together, thereby to provide a normally self-sustaining form, girdles encircling said form and spaced longitudinally thereof, each of said girdles comprising bars bearing edgewise against the outer edges of said flanges and overlapped upon each other at corners of the form, said bars having inclined slots formed therethrough with the slots in overlapping portions of the bars being adapted to be brought into register with each other, and wedges 20
- located in registering slots and cooperating with the bars to crowd them against the sides of the form and thereby to tighten the girdle around the form. 25
7. A form for making flat sided concrete columns, comprising a series of sheet metal units of channel section extending longitudinally of the form to support the sides of the column, additional sheet metal units of angular section extending longitudinally of the form at the corners of the column, said units being arranged edge to edge with their flanges in abutting relationship, and means for removably fastening the flanges of said units rigidly together. 30
8. A form for making concrete columns, comprising a series of sheet metal units extending longitudinally of the form to support the sides of the column, each of said units having marginal flanges extending longitudinally thereof and projecting backwardly away from the column, said flanges being slotted to receive slotted keys, and wedges located in the slots of said keys and cooperating with them to secure the abutting flanges of adjacent units rigidly but releasably together. 35
